UNITED STATES PATENT OFFICE.

HENRY HENTHORNE, OF NEWARK, OHIO.

FENDER OR LIFE-GUARD.

SPECIFICATION forming part of Letters Patent No. 536,806, dated April 2, 1895.

Application filed June 25, 1894. Serial No. 515,553. (No model.)

To all whom it may concern:

Be it known that I, HENRY HENTHORNE, of Newark, in the county of Licking and State of Ohio, have invented certain new and useful Improvements in Fenders or Life-Guards; and I do hereby declare the following to be a full, clear, and exact description of the invention, such as will enable others skilled in the art to which it pertains to make and use the same.

My invention relates to improvements in fenders or life-guards for locomotives and motor-cars, the object being to provide a fender or life-guard that shall not only be capable of clearing the track of any obstruction in advance of the locomotive or motor, but shall also be capable of catching a person or animal in front of the locomotive or motor without any liability of the person or object, caught by the fender or life-guard, rolling or being thrown therefrom.

With this object in view, and to the end of attaining certain other advantages, herein-after specified, my invention consists in certain features of construction, and in combinations of parts, hereinafter described and pointed out in the claims.

In the accompanying drawings, Figure 1 shows my improved fender or life-guard in position upon a motor-car, showing the operating-parts of the fender or life-guard in position ready to operate. Fig. 2 is a perspective view, showing my improved fender or life-guard with the working parts in position after operation. Fig. 3 is a side elevation, partly in section, of the fender or life-guard showing the working parts in position to operate. Fig. 4 is a view, looking in the direction of the arrow, Fig. 3, with portions broken away and in section to more clearly show the construction and to reduce the size of the figure.

My improved fender or life-guard comprises preferably two triangular frames A located such a distance apart that they, in the application of the fender or life-guard, shall come or approximately come in line with the rails R of the railway-track. Said frames, at the bottom and outer and inner ends are preferably connected together and braced apart by

rods B and said frames are also connected at the top and inner end by means of a rod C.

A bail-shaped frame E extends from the one side-frame to the other side-frame of the fender or guard, and has its end-members e pivotally secured, as at e', to said frames, whereby said bail-shaped frame is capable of oscillation, the movement of said frame inwardly being limited by the diagonally arranged member of the triangular frame A.

A piece of suitable fabric or material G extends from the upper end fender or guard downwardly to the central member of bail-shaped frame E. The length of said piece of fabric or material is such that it will accommodate the oscillation or movement of frame E outwardly in the direction of the rails of the track, the rails serving as stops to limit the oscillation of said frame in that direction, and the length of said piece of fabric or material is preferably such that when the aforesaid bail-shaped frame is in its outwardly-tilted position as shown in Figs. 1, 3 and 4, said fabric or material shall be stretched taut, or approximately so, and so that when said bail-shaped frame is in its inwardly-tilted position as shown in Fig. 2, said fabric or material shall be loose and form a pocket, as shown in said figure.

A roller I, extending from one side-frame A to the other, is supported by said frames a suitable distance inwardly of the connection of bail-shaped frame E with said frames, and a curtain or apron K is suitably secured to said roller, said apron or curtain being adapted to be wound upon or paid out by said roller according as the latter is rotated in the one direction or the other, the one trunnion of said roller being preferably extended a suitable distance outside of the supporting-frame, as at I', said outer end of the trunnion referred to being suitably shaped to receive a crank for turning the roller. Curtain or apron K leads from roller I outwardly to and over the central member of the bail-shaped frame E and over the fabric G connected with said bail-shaped frame. Curtain or apron K, at its outer end, and near its side edges, is suitably connected, preferably by means of chains L, with spring-actuated spools or drums 100

M suitably supported at the upper end of the device, said chains or flexible connections being wound upon or paid out by said drums according as the latter are rotated in the one direction or the other, the springs M' of said drums or spools acting in the direction to rotate the drums in the direction to wind up the aforesaid chains or flexible connections.

By the construction hereinbefore described,

- 10 it will be observed that when the working parts are in their normal position, as shown in Figs. 1, 3 and 4, with bail-shaped frame E in its outwardly oscillated position, with fabric G taut or approximately so, and with curtain or apron K wound upon roller I, some suitable means for holding the parts in the position indicated, against the action of springs M must be provided, and the locking means preferably provided for the purpose
- 15 20 comprises a dog O suitably secured to each of the chains or connections L and projecting laterally through a longitudinal slot a in the inclined or diagonally arranged member of the adjacent side-frame A of the fender or guard.

- 25 The arrangement of parts is such that when the working parts, hereinbefore described, are in their normal position, as shown in Figs. 1, 3 and 4, the aforesaid dogs on chains or members L are in position at or near the lower end of the slots a in frames A and the working parts are held in such position by means of latches or locking-levers P fulcrumed, as at P', to frames A. Levers or latches P have hook-shaped arms P² adapted to engage dogs and lock the latter and connected parts in their normal position. Latches or levers P are also provided with arms P³ adapted, as will presently appear, to be engaged by bail-shaped frame E when the latter is oscillated
- 30 35 40 inwardly.

- 45 It will be observed that, in the normal position of the parts, bail-shaped frame E declines outwardly into close proximity to the rails of the track, so that, in case of an obstruction on the track, said obstruction will be engaged by the central member of frame E and pushed along the track in advance of the fender or guard. The arrangement of parts is, however, such that should a person 50 or animal fall or be thrown in front of the motor, the fender or guard will pick up such person or animal and cause him or it to be thrown onto fabric G, resulting in the depression of said fabric and, in the inward oscillation of bail-shaped frame E into engagement with arms P³ of levers or latches P, resulting in the actuation of said latches or levers to unlock, thereby releasing chains or connections L free to be wound up by spring-actuated drums M, and unwinding the curtain or apron from roller I as shown in Fig. 2 and drawing said curtain or apron over or partially over the person or animal lodged upon the depressed or pocket-forming fabric G, and 55 60 65 the parts are automatically held and locked

in their operative position by hook-shaped arms P⁴ of levers P, which lever-arms P⁴ engage the central member of frame E in said position of the parts, as shown in Fig. 2, and curtain or apron K and the chains or devices connecting said apron or curtain with drums M are locked in the drawn position of said apron or curtain by the engagement of the dogs on the chains with notches a' formed in frames A and in open relation with slots a in said frames.

I would remark that fabric G is preferably netted, reticulated or perforated to accommodate the free passage of the air therethrough, so that the force of the wind shall not operate the guard or fender. I would also remark that the space within the triangular frames A is preferably closed by some suitable fabric or material S to prevent the person or object picked up by the fender or guard from being dislodged through said frames.

What I claim is—

1. In a fender or life-guard for locomotives and motor-cars, the combination of two triangular frames A A located a suitable distance apart, an oscillating frame E pivotally supported from the lower and outer ends of the aforesaid triangular frames, a piece of fabric or material G extending from the upper and inner end of the guard or fender to and connected with said oscillating-frame, a roller I suitably supported at the outer and lower end of the guard or fender and a curtain or apron K attached to and normally wound upon said roller, chains or flexible connections L connected with said apron or curtain, spring-actuated spools, drums or suitable devices M for automatically winding up said flexible connections and unwinding the aforesaid apron or curtain, suitable mechanism for locking the working parts in their normal position against the action of the aforesaid spring-actuated devices, said locking-mechanism being adapted to be actuated to unlock by a load brought to bear upon the aforesaid fabric or material G, substantially as set forth.

2. In a life-guard or fender for locomotives and motor-cars, the combination of triangular frames A A located a suitable distance apart, pivoted bail-shaped frame E, piece of reticulated, netted or perforated fabric or material G, roller I, curtain or apron K, chains or flexible connections L provided with dogs or projecting members O, spring-actuated spools, drums or devices M, and locking-levers or latches P having arms P² P³ and P⁴, all arranged and operating, substantially as set forth.

3. In a fender or life-guard for locomotives and motor-cars, the combination of triangular frames A A arranged a suitable distance apart and suitably connected and braced apart, said frames being slotted, as at a, and notched, as at a', bail-shaped frame E; piece of fabric or material G; roller I; apron or curtain K; 125

spring-actuated spools, drums or winding devices M; chains L provided with dogs or projecting-members O; latches or levers P provided with hook-shaped arms P² and P⁴ and 5 an arm P³, the parts being arranged and operating substantially as shown, for the purpose specified.

In testimony whereof I sign this specification, in the presence of two witnesses, this 6th day of March, 1894.

HENRY HENTHORNE.

Witnesses:
